Primary Examiner — Leanne Was-Englehart(57) **CLAIM**

The ornamental design for a fence rail set, as shown and described.

DESCRIPTION

FIG. 1 is a front view of a fence rail set showing my new design;

FIG. 2 is a rear view of the fence rail set;

FIG. 3 is a right side view of the fence rail set;

FIG. 4 is a left side view of the fence rail set;

FIG. 5 is a top view of the fence rail set;

FIG. 6 is a bottom view of the fence rail set;

FIG. 7 is an exploded top front side perspective view of the fence rail set in use; and,

FIG. 8 is a detailed top front side perspective view taken from FIG. 7.

The dot-dot-dash broken line circles in FIGS. 7 and 8 depict the limits of the enlarged/detail view and form no part of the claimed design. The other broken lines in FIGS. 7 and 8 are illustrative of environmental structure forming no part of the claimed design.
